UNITED STATES PATENT OFFICE

JOHN POST, OF PHILADELPHIA, PENNSYLVANIA.

BRAKE-ACTUATING DEVICE.

No. 823,966.

Specification of Letters Patent.

Patented June 19, 1906.

Application filed February 12, 1906. Serial No. 300,796.

To all whom it may concern:

Be it known that I, JOHN POST, a citizen of the United States, and a resident of Philadelphia, in the county of Philadelphia and 5 State of Pennsylvania, have invented certain new and useful Improvements in Brake-Actuating Devices, of which the following is a specification.

My invention relates to devices for actuating car-brakes; and it consists in securing the brake-shoes to arms secured to the piston-rods of steam-cylinders and also the provision of a steam-circulating system connecting said cylinders with controller-valves at each end of the car, which valves are in turn connected with a steam-boiler. Valves are also provided in the pistons of the cylinders to drain the cylinders and conduits of the water of condensation, said valves being so constructed that they open automatically when the steam-pressure ceases and are closed by the steam-pressure and remain closed while the pressure of steam is on.

The construction and advantages of my invention will be explained in detail herein-after and illustrated in the accompanying drawings, in which—

Figure 1 is a plan view of the under portion of a car, showing particularly the system employed in my improved brake; Fig. 2, a side view; Fig. 3, an enlarged view, in vertical section, of one of the cylinders and the piston therein, showing the drain-valve; Fig. 4, a view of the bottom of the cylinder; Fig. 5, a detail view of one of the controller-valves, and Fig. 6 a side view of one of the transverse pipes connecting the cylinders.

Similar reference characters indicate corresponding parts throughout the several views.

A represents a pipe connected with any source of live steam, such as a boiler carried by the car for supplying steam to a motor for driving the vehicle, it being thought unnecessary to illustrate this structure, as any other source, such as a boiler of a locomotive, may be substituted without affecting the spirit of my invention.

B represents a controller-valve located on the platform at each end of the car and consisting of a casing C, in which is mounted the valve-piston D, operated by means of a crank-handle secured to operating-rod D', revolvably mounted in a boxing F, mounted on the platform, said crank-handle being conveniently positioned for operation by the

motorman or brakeman standing on the platform.

G represents a pipe connecting each valve-casing C with steam-pipe A.

H represents the brake-shoes suspended 60 by means of brackets I from the car-body, J representing the wheels, which are shown mounted on double trucks, though it is apparent that triple-wheeled trucks may be substituted, if desired.

K represents a cylinder secured above each pair of brake-shoes H, with a piston L therein held normally in a raised position by a coil-spring M. The lower end of the cylinder K is open and provided with a central 70 bearing N, connected with the sides of the cylinder by means of radial arms n.

O represents the piston-rod, secured to piston L and slideable in bearing N. The brake-shoes H are connected with the free end of 75 piston-rod O by means of arms o, said arms forming a toggle-joint, so that when the piston-rod O is pushed downward by the action of the steam, as hereinafter described, the brake-shoes are pushed against the tread of 80 the wheels J.

P represents a pipe extending transversely of the car and connected with the tops of cylinders K; Q, pipes connecting each valve-casing C with the adjacent pipe P, and R a 85 pipe connecting the pipes P, suitable couplings S being provided to connect said pipes together. The pipes P are made higher in their middle portions than at their ends, so that the water and steam contained therein 90 after the live steam has been cut off drains toward the cylinders at each end thereof, while the pipes Q are arranged so that they drain toward the pipes P, being higher at their ends secured to the controller-valves 95 than where connected with pipes P, and pipe R for the same reason is made higher in its middle than at its ends where connected with pipes P. It will be understood from this construction that all the pipes drain toward the cylinders K. A drain-valve is provided in each piston L, consisting of an opening T in the piston, having its lower end pro-

vided with a perforated diaphragm U with a central bearing u to receive the valve-stem v, 105 secured to the valve-piston V, W representing a button or head on the lower end of the stem to limit the upward movement of the valve under the impulse of coil-spring X. Said coil-spring X has sufficient tension to raise 110

the valve V only when the pressure of the steam is cut off, but allowing the valve to close when the steam is turned into pipes Q, P, and R and cylinders K.

5 V represents a shoulder on the inner side of the upper end of each cylinder K to limit the upward movement of the piston L therein under the impulse of spring M, so that a chamber Z is provided in the cylinder to receive the steam and the operation of the drain-valve piston V is not interfered with.

It will be understood from this description that when the valve-piston D at either or both ends of the car is opened by turning the 15 crank-handle E the steam entering the pipes Q will pass into the pipe P adjacent to the piston D and through pipe R to the other pipe P, closing the drain-valves U and passing into cylinders K, depress the pistons L there- 20 in, and acting through arms O set the brake-shoes H on the heads of wheels J, the pressure of the brake-shoes H being governed by the amount of steam admitted to said pipes.

When the piston-valve D is turned so as to 25 shut off the steam from the pipes P, Q, and R, the springs M return the pistons L to their normal position, upsetting the brakes, and at the same time the springs X open the drain-valves V to drain the steam and water of condensation from said pipes and cylinders.

Having thus described my invention, what I claim is—

1. In a car-brake, cylinders, pistons in said cylinders, the brake-shoes operatively connected with said pistons, a pipe connected with a source of steam, controller-valves, tubular connections between said valves and the steam-pipe, tubular connections between said valves and the cylinders, all of said pipes 40 and tubular connections arranged so as to drain to said cylinders, and means to drain said cylinders, substantially as shown and described.

2. In a car-brake, cylinders, pistons in said cylinders, coil-springs in said cylinders bearing against said pistons, the brake-shoes operatively connected with said pistons, a steam-pipe, controller-valves, tubular connections between said valves and the steam-pipe, tubular connections between said valves and the cylinders, all of said pipes and tubular connections arranged so as to drain to said cylinders, and means to drain said cylinders, substantially as shown and described.

3. In a car-brake, cylinders, pistons in said cylinders, the brake-shoes operatively connected with said pistons, a steam-pipe, controller-valves, tubular connections between said valves and the steam-pipe, tubular connections between said valves and the cylinders, and drain-valves in said pistons to relieve the cylinders and connecting-pipes of water of condensation, substantially as shown and described.

4. In a car-brake, cylinders, pistons in said

cylinders, the brake-shoes operatively connected with said pistons, a steam-pipe, controller-valves, tubular connections between said valves and the steam-pipe, tubular connections between said valves and cylinders, 7c said tubular connections arranged to drain into said cylinders, valves in said pistons, and springs to actuate said valves when steam is cut off from said cylinders to drain the tubular connections and cylinders of water of condensation, substantially as shown and described.

5. In a car-brake, cylinders, pistons in said cylinders, coil-springs in said cylinders bearing against said pistons, the brake-shoes operatively connected with said pistons, a steam-pipe, controller-valves, tubular connections between said valves and the steam-pipe, tubular connections between the valves and the cylinders, and drain-valves in said 85 pistons to relieve said cylinders and tubular connections of water of condensation, substantially as shown and described.

6. In a car-brake, cylinders, pistons in said cylinders, coil-springs in said cylinders bearing against said pistons, the brake-shoes operatively connected with said pistons, a steam-pipe, controller-valves, tubular connections between said valves and the steam-pipe, tubular connections between the valves and the cylinders, said tubular connections arranged to drain into said cylinders, valves in said pistons, and springs to actuate said valves to open them when the supply of steam is cut off from said cylinders, substantially as shown and described.

7. In a car-brake, cylinders, pistons in said cylinders, coil-springs in said cylinders bearing against said pistons, a piston-rod secured to each piston, brake-shoes, arms connecting 105 said brake-shoes and piston-rods, transverse pipes connecting said cylinders in pairs and arranged to drain into said cylinders, a pipe connecting said transverse pipes and arranged to drain thereinto, controller-valves, 110 pipes connecting said controller-valves and transverse pipes and arranged to drain thereinto, a valve in each piston, a coil-spring to lift each valve, and a pipe connected with each controller-valve and a source of steam-supply, substantially as shown and described.

8. In combination with a railway-car having a platform at each end, cylinders, pistons in said cylinders, the brake-shoes operatively connected with said pistons, a pipe connected 120 with a source of steam, a controller-valve mounted on each platform, tubular connections between said valves and the steam-pipe, and tubular connections between said valves and the cylinders, substantially as 125 shown and described.

9. In combination with a railway-car having a platform at each end, cylinders, pistons in said cylinders, the brake-shoes operatively connected with said pistons, a pipe connect- 130

ed with a source of steam, a controller-valve mounted on each platform, tubular connections between said valves and the steam-pipe, tubular connections between said valves and the cylinders, and means to drain said pipes, cylinders and tubular connections, substantially as shown and described.

10. In combination with a railway-car having a platform at each end, cylinders, pistons in said cylinders, the brake-shoes operatively connected with said pistons, a pipe connected with a source of steam, a controller-valve mounted on each platform, tubular

connections between said valves and steam-pipe, tubular connections between said valves and the cylinders, and spring-actuated drain-valves in said pistons to drain the cylinders, pipes and tubular connections, substantially as shown and described.

15. In witness whereof I have hereunto signed my name in presence of two subscribing witnesses.

JOHN POST.
